UNITED STATES PATENT OFFICE

PIERRE KEROUANTON, OF MARIEVAL, SASKATCHEWAN, CANADA

AUTOMATIC NEEDLE-VALVE CLOSER

Application filed April 30, 1929. Serial No. 359,370.

This invention relates to a device to automatically close a needle valve on a gasoline engine and thereby stop the said engine. The primary object being to provide such a device that will, in conjunction with an alarm clock of standard make, stop an engine to which it is attached at any predetermined time.

A further object is to provide such a mechanism that is simple, efficient, and inexpensive to manufacture and that will not easily become inoperative or get out of order.

The advantages of this invention are numerous for instance a farmer may set an engine equipped with the device to pump water for a specified length of time and then go to some distant field and leave the engine unattended knowing that the gasoline supply will be closed and the engine stopped when the time has elapsed.

With these and other objects in view as will appear as the description proceeds, the invention consists in the novel construction and arrangement of parts as hereinafter more specifically set forth, claimed and shown in the accompanying drawings forming a part of this present application and in which:

Figure 1 is a front elevation of my invention showing alarm clock secured to the same.

Figure 2 is a plan view of the slotted plate by which the device is connected to the needle valve.

Figure 3 is a rear elevation of the device with alarm clock in place.

Figure 4 is a plan view, with the clock and part of the frame omitted.

Referring more in detail to the drawings in which similar reference characters designate corresponding parts throughout the several views it will be seen that the invention comprises a frame 10 to which is secured a shoe 11 at right angles thereto. On the top of said shoe 11 are located a pair of angle brackets 12 designed to suit the alarm clock 13 which is of standard manufacture throughout. These brackets 12 are bolted to the shoe 11 and the legs of the clock securely fastened to the brackets to hold the clock rigidly to the frame. 14 is the main shaft and is pivoted in the shoe at 15 and supported

in the frame 10 by the bearing 16. Wound about this shaft is a spring 17 having one end secured to the said shaft and the other end secured to the spring casing 18 in which it is enclosed. The said spring casing being fastened to the shoe 11. A lever 19 extends at right angles from the shaft 14 as a means of turning the said shaft as will be explained later. A toothed ratchet wheel 20 is also mounted on the shaft 14.

Mounted in the side of the shoe 11 is a lever 21 which extends upwards to the alarm winding key 22 on the clock 13 and is designed to rest against the lower part of same. This lever 21 is controlled by a spring 23 secured at one end to the said lever and at the other end to the screw 24 in the frame 10. An arm 25 is bolted to that part of the lever 21 which extends through the shoe 11. Pivoted on the main frame is a catch 26 having a pointed end 27 to engage the teeth of the ratchet wheel 20. A spring 28 is provided to keep the catch in connection with the ratchet wheel. This spring is secured to the outer end 29 of the catch 26 and to a cotter pin 30 in the frame 10. This catch is connected to the arm 25 by means of a link 31.

At the lower end of the main shaft is secured a slotted plate 32 as a means of connecting the device to the pins on the upper end of the usual type of needle valve stem. This part may be designed to suit conditions. The main frame 10 may also be drilled to suit the particular make of engine on which the invention is to be used.

The manner of operating the invention is as follows:

The alarm is wound and set to the time it is desired that the engine should be stopped. The engine is now started and the needle valve opened and adjusted by means of the lever 19. It will be noticed that in turning the shaft to set the needle valve, the spring 17 is wound tighter around the shaft 14. Now the lever 21 is brought to rest against the alarm winding key 22 and the catch 26 is permitted to engage the sprocket wheel 20 which prevents the shaft 14 from turning.

When the alarm is released the key 22 turns as shown by the arrows Fig. 3, which permits

the lever 21 to be pulled downwards by the spring 23. This causes the catch 26 to be disengaged from the sprocket wheel by means of the arm 25 and the connecting link 31 and permits the shaft 14 to be turned by the spring 17 unwinding. Note that the shaft will only be turned a similar number of revolutions by the unwinding of the spring as it was by the winding up of the spring when the needle valve was being opened, and will therefore, be just sufficient to close the said needle valve and stop the engine.

It is believed that the construction and advantages of the structure shown may be apparent from the foregoing paragraphs taken in connection with the accompanying drawings without further detailed description.

While the preferred embodiment of the invention has been disclosed, it is understood that minor changes in the details of construction, combination and arrangement of co-operating parts may be resorted to within the scope of what is claimed without departing from the spirit of the invention.

25 What I claim is:—

In an automatic needle valve shutter for use on a gasoline engine; a main frame member having a secondary frame secured thereto; a shaft mounted in a bearing in the main frame and pivoted at its upper end in the secondary frame; a shaft adjusting lever extending at right angles from said shaft; a spring enclosed in a spring case, said case being secured to the secondary frame; the spring being fastened to the shaft on its inner end and to the case at its outer end; a toothed wheel mounted on said shaft; a catch pivoted on main frame to engage said toothed wheel; an alarm clock mounted on the secondary frame; a lever pivoted in the secondary frame extending upwards to engage the winding key on the alarm clock, a spring to control said lever; a connecting arm and link from the lever to the aforementioned toothed wheel catch; and a means of connecting the lower end of the shaft to the needle valve stem of the gasoline engine, substantially as set forth.

50 In testimony whereof I affix my signature.
PIERRE KEROUANTON.
